(57) **CLAIM**

The ornamental design for a ride-on toy car, as shown and described.

DESCRIPTION

FIG. 1 is a front, right and bottom perspective view of a ride-on toy car, showing my new design;
FIG. 2 is a rear, left and top perspective view thereof;
FIG. 3 is an enlarged top plan view thereof;
FIG. 4 is an enlarged bottom plan view thereof;
FIG. 5 is a left side view thereof;
FIG. 6 is a right side view thereof;
FIG. 7 is an enlarged rear view thereof;
FIG. 8 is an enlarged front view thereof; and
FIG. 9 is an enlarged view of area 9 taken from FIG. 1 thereof.

FIG. 10 is an enlarged view of area 10 taken from FIG. 1 thereof.

FIG. 11 is an enlarged view of area 11 taken from FIG. 2 thereof.

FIG. 12 is an enlarged view of area 12 taken from FIG. 2 thereof.

FIG. 13 is an enlarged view of area 13 taken from FIG. 3 thereof; and,

FIG. 14 is an enlarged view of area 14 taken from FIG. 8 thereof.

The dot-dash broken lines depict the boundaries of the enlargements that form no part of the claimed design. The broken lines shown in the drawings illustrate portions of the ride-on toy car that form no part of the claimed design.
